COLLAPSIBLE GARMENT HANGER
AND FORMBenjamin Wexler and Marvin C. Wexler,
Philadelphia, Pa.

Application September 14, 1951, Serial No. 246,554

6 Claims. (Cl. 223—68)

1

This invention relates generally to garment forms of the class wherein the form may be collapsed to serve as a hanger for the garment and is more particularly concerned with a construction affording improved means for displaying a garment draped on such a form, and also affording particular advantage as to the manner in which such a form functions.

Garment forms that are collapsible into the shape of relatively flat units are known. Such a form, when expanded, is commonly used for filling out the upper body portion of a garment, for example, a dress that is to be displayed for sale, the collapsed form being used as an ordinary hanger. Known dress forms of the class hereinabove referred to have not been entirely satisfactory because the upper chest and upper back portions of these forms do not conform as closely with the contour of the corresponding portions of the human body as do known forms that are not collapsible. In addition, known collapsible dress forms present undue difficulty in the expansion thereof from collapsed condition and in the maintenance thereof in either expanded or collapsed condition.

Accordingly, it is an object of this invention to provide a combination dress form and hanger, which in expanded condition, affords adequate means about the neck opening of a dress draped thereon for supporting the same, the aforementioned means being formed to correspond to the shoulders and the upper chest and upper back portions of the human body, and which in collapsed condition forms a relatively flat unit suitable for use as a hanger.

Another object of this invention is to provide such a combination dress form and hanger with means for positively securing the form in collapsed condition, the aforementioned means being releasable for positively expanding the form and maintaining it in such condition.

And accordingly, this invention may be considered as comprising the various features of construction and/or combination affording one or more of the above stated and other objects and advantages as hereinafter more particularly pointed out in the following detailed description and appended claims, reference being had to the accompanying drawing of an illustrative apparatus, in which:

Figure 1 is a perspective view looking at the back of an apparatus incorporating the present invention and showing the combination dress form and hanger expanded, some of the fabric being broken away to expose part of the frame structure.

2

Figure 2 is a front view of the apparatus shown in Figure 1, the fabric being broken away to expose the frame structure.

Figure 3 is a plan view on line 3—3 of Figure 2, the fabric being omitted.

Figure 4 is a perspective view of a portion of the frame structure.

Figure 5 is a side view of the apparatus shown in Figure 1, the fabric being shown in section to expose the frame structure, part of which is broken away to expose the central interior construction thereof.

Figure 6 is an enlarged view of an upper portion of the frame structure in the position thereof shown in Figure 2, parts being broken away for the sake of clarity.

Figure 7 is similar to Figure 5, but shows the frame structure in collapsed condition.

Figure 8 is an enlarged section on line 8—8 of Figure 7 showing the assembly for actuating the folding frame sections.

Figure 9 is a perspective view of an upper portion of the frame structure in the position shown in Figure 8.

Figure 10 is an enlarged section on line 10—10 of Figure 8.

Figure 11 is an enlarged section on line 11—11 of Figure 6.

Referring now to the drawings it will be seen that the apparatus chosen to illustrate the present invention is a frame structure which, when covered with a suitable material 11, affords a form closely resembling the trunk of the human body. The frame structure comprises a main frame section 12, folding frame sections 13 to 19, inclusive, and an assembly 21 for actuating the latter.

The main frame section 12 includes a main member 22 and cross members 23, 24 and 25. Main member 22 is made of suitably heavy wire stock and comprises a pair of similar pieces 26—26 having opposed end portions rigidly connected together by a pair of plates 27—27 and rivets 28. The pieces 26—26 are shaped to outline the shoulders, bust, waist and hips of the human body, and opposed portions thereof at the bust, waist and hip lines are rigidly connected together respectively by cross members 23 to 25, inclusive, each of the latter being made of suitably heavy wire stock and comprising a pair of similar pieces 29 having opposed end portions rigidly connected together by a plate assembly 31 and rivets 32.

Plates 27—27 are directly secured together by rivets 33 and the upper end portions thereof are flanged in opposite directions as at 34—34 to provide a seat for a plate 36, the latter being

secured to flanges 34—34 in any suitable manner and having an opening 37 in a centrally disposed portion thereof. Opposed portions of plates 27—27 are oppositely offset as at 38—38, the offset portions together forming a guideway 39 disposed on the central longitudinal axis of the frame structure.

The plate assembly 31 comprises four similar plates 41 each having a pair of legs 42—43 disposed at right angles to one another. The legs 42—43 are suitably arranged back to back, and pairs of legs 42 and of legs 43 are directly secured together, the former by rivets 44 and the latter in any suitable manner, each opposed end portion of pieces 29 being disposed between a pair of legs 42, and each pair of legs 43 affording a pivot support. The portions of plates 41 where legs 42—43 come together are offset as at 45, the offset portions together forming a guideway 46 disposed on the central longitudinal axis of the frame structure in axial alignment with guideway 39 and opening 37 in plate 36, and rigidly mounted in the guideway 46 formed by the lowermost plate assembly 31 is a tubular guide sleeve 40. Pairs of pivot support plates 47 are rigidly secured in any suitable manner to opposed side portions of the main frame member 22 at the bust, waist and hip lines, each plate 47 having opposite end portions thereof projecting respectively beyond the front and rear of the main frame member 22. Openings formed in the opposite end portions of each pair of plates 47 are disposed in axial alignment with similar openings in the associated pivot support legs 43 of plates 41.

Each of the folding frame sections 13 to 18, inclusive, is made of wire stock and comprises a piece 48 having opposite end portions 49 similarly offset in the same direction from a main body portion, and also comprises a rib 51 terminally rigidly secured to the main body portion in any suitable manner, and disposed thereby to extend therefrom in the same direction as the offset opposite end portions 49 of piece 48. Folding frame sections 13 and 14 are disposed at the bust line, frame sections 15 and 16 are disposed at the waist line, and frame sections 17 and 18 are disposed at the hip line, frames 13, 15 and 17 being further disposed in front of main frame section 12, and frames 14, 16 and 18 being further disposed to the rear thereof. In this connection, it will be seen that each of the aforementioned frames, except folding frame 14, is horizontally disposed when the form is expanded, and that frame 14 is inclined upward to the rear when the form is expanded. The free end portions of rib 51 and the offset end portions 49 of each of the aforementioned folding frame sections are suitably disposed for pivotal connection to the associated pivot supports 43 and 47, the aforementioned parts all having transversely aligned openings which receive pivot pins 52.

The folding section 19 includes a shoulder plate 53 rigidly secured to the upper portion of the main frame section 12 by screws 54 and a stiffener plate 55, the latter being secured to the underside of a flange 34 in any known manner. Plate 53 is shaped to conform to the contour of the major portion of the shoulders and the adjoining upper back at the base of the neck. A chest plate 56 is hinged as at 57 to opposite end portions of plate 53, being shaped to conform with the contour of the upper chest, and a back plate 58 is hinged as at 59 to an intermediate portion of plate 53, being shaped to conform with

the contour of the upper back. Each of the plates 56 and 58 have stiffening ribs formed therein as at 60.

The assembly 21 for actuating the folding frame sections 13 to 19 comprises a rod 61 and a tubular member 62 fitted over the upper end portion thereof, both being hooked as shown. At a lower end portion of the rod a short tubular sleeve 63 is fitted over the rod 61 and rigidly secured in place in any suitable manner. Mounted on spaced portions of rod 61 between tubular member 62 and tubular sleeve 63 and just above the bust, waist and hip lines, respectively, are three collars 64, a similar collar 65 being mounted on rod 61 in end abutting relation to tubular member 62. A pair of tubular spacers 66 are mounted on rod 61 between collars 64, and a tubular spacer 67 is mounted between the uppermost one of collars 64 and collar 65, all for the purpose of securing said collars against axial movement relative to rod 61. Mounted on the lowermost one of tubular spacers 66 is a compression spring 72 seated against spring seat washers 73—73 at opposite ends thereof.

The assembly 21 is mounted in guideways 39 and 46 and in tubular guide sleeve 40, tubular member 62 being slidably and turnably received by guideway 39, tubular spacers 66 being similarly received by the associated guideways 46 and the lower extremity 68 of rod 61 being similarly received by tubular guide sleeve 40.

A portion of rod 61 and tubular member 62 just below the hooked portion thereof mounts a pin 69 having opposite end portions thereof projecting outwardly therefrom, and opposed portions of plates 27—27 are oppositely offset as at 70—70 to permit movement of the opposite end portions of pin 69 therebetween. Also, the opening in plate 36 is formed as at 71—71 to permit passage of the opposite end portions of pin 69 therethrough.

Each folding frame 13 to 18, inclusive, is connected to the assembly 21 by means of a link 74 having opposite end portions pivotally connected respectively to the associated collar 64 and an intermediate portion of the associated rib 51. The folding frame 19 is similarly connected to assembly 21 by means of links 76—76 having opposite end portions pivotally connected respectively to collar 65 and intermediate portions of chest plate 56 and of back plate 58. And it will be understood that links 74 and 76—76 may be considered as parts of the assembly 21.

Referring particularly to Figures 1—6, the frame structure is shown in expanded condition, the fabric covering the frame structure closely resembling the trunk of the human body. The assembly 21 is in its lowermost position relative to main frame section 12, pin 69 being in the position shown in Figure 6. The compression spring 72 acts between the plate assembly 31 disposed at the waist line and the lowermost one of collars 64 and by so doing urges the assembly 21 downward relative to main frame section 12, relative downward movement being limited by abutment 65 of the opposed end portions of tubular sleeve 63 and tubular guide sleeve 40. The links 74 and 76 act as braces between the collars and the folding frame sections with which they are connected, thus restraining the latter against folding movement.

Now referring particularly to Figures 7, 8 and 9, when the operator wishes to collapse the form, he grasps the hooked end of tubular member 62 with one hand and pulls upward against the action of spring 72 while pressing downward on

main frame section 12, as on plate 36, with the other hand. The assembly 21 will move upward relative to main frame section 12, pin 69 moving upward between plates 27, tubular member 62 sliding in guideway 39, tubular spacers 66 sliding in the associated guideways 46, and the lower extremity 68 of rod 61 sliding in tubular guide sleeve 40. In moving from the position of Figure 5 to that of Figure 7, links 74 and 76 are in tension, thus acting to swing the folding frame sections inward against main frame section 12.

Referring particularly to Figure 5, it will be noted that a line passing through the pivoted connections at opposite ends of any one of the links 74 or 76 is inclined upward and inward toward the center of the frame structure. In addition, it will be noted that the axes of hinges 57 and 59 are disposed respectively above the pivoted connections of links 76 to the chest plate 56 and the back plate 58. Consequently, when the assembly 21 is pulled upward relative to the main frame section 12, the folding frame sections 13 to 19 inclusive are folded against the main frame section 12 from the position shown in Figure 5 to that of Figure 7, sections 13 to 18, inclusive, swinging upward, and plates 56 and 58 of folding frame section 19 swinging downward.

To secure the folding frame sections 13 to 19, inclusive, in their folded positions the operator turns rod 61 about its longitudinal axis relative to main frame section 12, and to collars 64 and 65 so that pin 69 is positioned crosswise of the slots 71 in plate 36 and then releases rod 61, allowing pin 69 to be held against plate 36 by the action of spring 72. To expand the form the operator turns rod 61 back again so that pin 69 is positioned to register with slots 71 in plate 36 and the openings between plates 27-27 formed by the opposed oppositely offset portions 70 thereof.

Upon so doing the assembly 21 is moved downward relative to the main frame section 12 as a consequence of the action of spring 72, pin 69 passing through slots 71 and between plates 27-27 from the position shown in Figure 9 to that of Figure 6. In moving from the collapsed position shown in Figure 7 to the expanded position shown in Figure 5 links 74 and 76 are in compression, thus acting to swing the folding frame sections outward from main frame section 12.

It should be obvious now that a combination dress form and hanger has been provided which, when expanded, affords adequate support about the neck opening of a dress draped thereon for displaying the dress to best advantage, and which, when collapsed, affords means for hanging the dress. In addition, the combination dress form and hanger provided incorporates positive means for securing it in collapsed position and for positively expanding the form and maintaining it in such condition, at the will of the operator.

It will be understood, of course, that the present invention is susceptible of various changes and modifications which may be made from time to time without departing from the general principles or real spirit thereof, and it is accordingly intended to claim the same broadly, as well as specifically, as indicated in the appended claims.

What is claimed as new and useful is:

1. In a collapsible garment form and hanger, a frame structure comprising an elongated flat main frame section, a plurality of folding frame sections each adapted to outline a portion of the human body and each carried by said main frame section for swinging movement between folded and expanded positions, said folding frame sec-

tions being disposed flat against said main frame section when in the former of said positions, and being disposed to suitably outline portions of the human body when in the latter of said positions, one of said folding frame sections presenting an outer surface conforming in shape to the shoulders and adjoining upper chest and upper back of the human body, a rigid elongated member carried by said main frame section and mounted for axial shifting movement relative thereto, said members being connected to said folding frame sections for simultaneous swinging movement thereof between said folded and expanded positions in response to said axial shifting movement, and spring means operatively associated with said member to normally urge it into such position relatively to said main frame structure as to maintain said folding frame sections fully expanded into body-conforming shape.

2. In a collapsible garment form and hanger, a frame structure comprising an elongated flat main frame section, a plurality of folding frame sections each adapted to outline a portion of the human body and each carried by said main frame section for swinging movement between folded and expanded positions, said folding frame sections being disposed flat against said main frame section when in the former of said positions, and being disposed to suitably outline portions of the human body when in the latter of said positions, one of said folding frame sections including a plate member rigidly secured to said main frame section and a pair of additional plate members pivotally secured to said first mentioned plate member for swinging movement relative thereto, a rigid elongated member carried by said main frame section and mounted for axial shifting movement relative thereto, said member being connected to said folding frame sections for simultaneous swinging movement thereof between said folded and expanded positions in response to said axial shifting movement, and spring means operatively associated with said member to normally urge it into such position relatively to said main frame structure as to maintain said folding frame sections fully expanded into body-conforming shape.

3. In a collapsible garment form and hanger, a frame structure comprising an elongated flat main frame section, a plurality of folding frame sections each adapted to outline a portion of the human body and each carried by said main frame section for swinging movement between folded and expanded positions, said folding frame sections being disposed flat against said main frame section when in the former of said positions, and being disposed to suitably outline portions of the human body when in the latter of said positions, one of said folding frame sections including a plate member rigidly secured to said main frame section and presenting an outer surface conforming in shape to the shoulders of the human body, and including a pair of additional plate members pivotally secured respectively to opposed edges of said first mentioned plate member for swinging movement relative thereto and presenting outer surfaces respectively conforming in shape to the upper chest and upper back of the human body, a rigid elongated member carried by said main frame section and mounted for axial shifting movement relative thereto, said member being connected to said folding frame sections for simultaneous swinging movement thereof between said folded and expanded positions in response to said axial shifting move-

7
ment, and spring means operatively associated with said member to normally urge it into such position relatively to said main frame structure as to maintain said folding frame sections fully expanded into body-conforming shape.

4. In a collapsible garment form and hanger, a frame structure comprising an elongated flat main frame section provided with a central opening, a plurality of folding frame sections each adapted to outline a portion of the human body and carried by said main frame section for swinging movement between folded and expanded positions, said folding frame sections being disposed flat against said main frame section when in the former of said positions, and being 15 disposed to suitably outline portions of the human body when in the latter of said positions, a rigid elongated member carried by said main frame section and mounted for shifting movement in said central opening, said elongated member being connected to said folding frame sections for swinging movement of the latter between said folded and expanded positions in response to movement of said elongated member, means on the latter operative to arrest movement thereof in one direction relative to said main frame section and to positively secure said folding frame sections in their folded positions, and yieldable means acting between said elongated member and main frame section for expanding said form.

5. In a collapsible garment form and hanger, a frame structure comprising an elongated flat main frame section including upper and lower end portions provided with coaxially alined openings, a plurality of folding frame sections each adapted to outline a portion of the human body and carried by said main frame section for swinging movement between folded and expanded positions, said folding frame sections being disposed flat against said main frame section when in the former of said positions, and being disposed to suitably outline portions of the human body when in the latter of said positions, a rigid elongated member carried by said main frame section and having axially spaced portions thereof disposed in said coaxially alined openings for shifting movement therein, said elongated member being connected to said folding frame sections for swinging movement of the latter between said folded and expanded positions in response to movement of said elongated member, pin means on the latter for arresting downward shifting movement thereof relative to said main frame section and positively securing said folding frame sections in their folded positions, a compression spring on said elongated member reacting against said main frame section when said arresting means is inoperative and shifting said elongated member downward relative to said main frame 60

section for expanding said form, and stop means on said elongated member to limit downward shifting movement of said elongated member relative to said main frame section.

5 6. In a collapsible garment form and hanger, a frame structure comprising an elongated flat main frame section including upper and lower end portions provided with coaxially alined generally vertically extending openings, a plurality of folding frame sections each adapted to outline a portion of the human body and carried by said main frame section for swinging movement between folded and expanded positions, said folding frame sections being disposed flat against said main frame section when in the former of said positions, and being disposed to suitably outline portions of the human body when in the latter of said positions, a rigid elongated member carried by said main frame section and having spaced portions thereof disposed in said generally vertically extending openings for vertical shifting and turning movement therein, said elongated member being connected to said folding frame sections for swinging movement of the latter between said folded and expanded positions in response to vertical movement of said shiftable member, a pin carried by the latter and presenting exposed opposite end portions positionable to abut the upper end portion of said main frame section for arresting downward shifting movement of said elongated member relative to said main frame section and positively securing said folding frame sections in their folded positions, a compression spring on said elongated member which, upon suitable turning of said elongated member, reacts against said main frame section to shift said elongated member and pin downward relative to said main frame section for expanding said form, said exposed end portions of the pin moving in said alined opening in the upper end portion of the main frame section during said downward shifting movement of the elongated member relative to the main frame section, and stop means on said elongated member to limit downward shifting movement of said elongated member relative to said main frame section.
